COMPENSATOR MECHANISM

Arnold A. Schwartz, Plainfield, N. J., assignor to
 Wood Newspaper Machinery Corporation,
 Plainfield, N. J., a corporation of Virginia

Application December 23, 1938, Serial No. 247,324

7 Claims. (Cl. 271—2.1)

In web printing presses are always used what are commonly known as compensator rolls. These rolls are so arranged in combination with other parts, that they engage the web so as to form an adjustable loop in the running web. The idea of this adjustable loop is to provide a means for matching margins, printing, etc., of sheets running through the press. This is for example, required before the sheets enter the folder, when it is required that the margins of the different sheets are in register, as well as that the complete pack of sheets is so adjusted that the cutting off mechanism in the folder will sever the sheets in the proper location.

In multiple color presses a compensator is required between each two adjacent impressions, this being the means whereby the colors from each impression are precisely deposited in matched relation to the previous impressions. The registering of margins or colors is always observed by the pressman at the delivery of the folder. For this reason it has been common practice to so arrange the compensator adjusting means that it could be operated by hand from a position close to the delivery. The common practice has been to lead an adjusting rod from each compensator to the adjusting position, from which place it then would be possible to operate each individual compensator by turning a hand wheel attached to each rod.

As it is quite common that a large number of compensators is required on a press it can be understood readily that this arrangement in several ways proves unsatisfactory, one of the difficulties being the cluttering up of the space around the folder with a cluster of rods and hand wheels. Another bad objection lies in the difficulty of the operator locating in the cluster the proper hand wheel belonging to the compensator which needs adjustment.

The objects of this invention are to reduce the above objection; to reduce to a single rod and single adjusting wheel the above mentioned cluster of rods and wheels; to make it possible to locate the proper compensator on a color press by simply pushing an adjusting button having the same color as the color being printed on the impression couple requiring adjustment; especially to provide a single means by which all the different compensators on the press may be operated, and to provide one hand operated rod running to all the compensators, but making the operation of any one of the compensators possible only, when pushing one of a series of buttons each assigned to one compensator, which,

by connection in an electric circuit, energizes a solenoid which connects the operating rod to the adjusting screw of the desired compensator.

Other objects and advantages of the invention will appear hereinafter. 5

Reference is to be had to the accompanying drawings, in which

Fig. 1 is a side view of the compensators and push button station of one embodiment of this invention; 10

Fig. 2 is a side view of the solenoid operating mechanism at each compensator therefor on enlarged scale;

Fig. 3 is an end view of the same.

Fig. 4 is a side view of parts shown in Fig. 2, 15 with the clutch open instead of closed;

Fig. 5 is an enlarged side view of one of the adjusting mechanisms;

Fig. 6 is a diagrammatic view and wiring diagram of a modification in which a motor replaces 20 the hand motion for turning the adjusting rod;

Fig. 7 is a similar view in which a ratchet motion is used for turning the adjusting rod, and

Fig. 8 is an end view of the ratchet motion of Fig. 7. 25

This invention is shown, especially in Figs. 1 to 5 inclusive, as applied to a color press, though the details of the press are not shown. The web supply and course of the web are shown as far as necessary to indicate some of the compensating 30 rolls 33.

An adjusting rod 10 is revolvably supported at each compensator position 14 and 16. The extreme end of this rod, next to the folder F is connected by mitres 13 and a rod 12 to an operating hand wheel 11. Looking especially at Figs. 2 and 3, the rod 10 is revolvably supported in bushings 17 of which the left end is pressed into a poppet 18. This poppet is in turn secured to a main support bracket 19 by a nut 20. On the opposite end of the bushing 17 is loosely fitted a bevel gear 21 which is kept from shifting endwise by a shoulder in the middle of the bushing 17 in one direction and by a collar 22, which is set screwed to the shaft 10, in the other direction. 45

The bevel gear 21 meshes with a larger bevel gear 23 which is revolvably fixed on a pin 24, this being an integral part of the poppet 18. A washer 35 and screwhead 36 prevent end motion of the gear 23. The bevel gear 23 also meshes 50 with a smaller bevel gear 25. This gear is secured to the upper end of an adjusting screw 26 which is revolvably secured to a bracket 27. It is kept from end motion by the gear 25 on the end of a screw rod and collar 28 which both 55

fasten to the rod on opposite sides of the bracket 27. The upper end of the bracket 27 is pivotally mounted on an extension of the poppet 1 allowing the screw 26 freedom to swing in the direction right and left as looking at Fig. 2.

The screw 26 engages the poppet 29 which is pivotally mounted in a fork in the end of a lever 30, Fig. 1. This lever is fixed to the outside end of a compensator support shaft 31 which extends across the press. At each side of the press inside of rails 34 are mounted levers 32, which carry and act as bearings for one of the compensator rolls 33. The shaft 31 is loosely mounted in holes in the rails 34, located at both sides of the press. On the lower ends of the screws 26 are fastened hand wheels 35, the purpose of which is to enable corresponding compensators to be adjusted from the local position, when desired.

From a study of the above description it will be found that up to now, the hand wheel 11 can be turned freely in either direction without accomplishing anything but revolving the main adjusting rod 10.

In the following will now be explained the mechanism which makes it possible to adjust any desired compensator by simply pushing one of the buttons 51, which is allotted to this specific compensator, and then turning the hand wheel 11.

Looking at Fig. 2 it will be found that the back end of the gear 21 is furnished with a clutch face of V-shaped jaws. In back of the mitre and slidably fitted to the rod 10 is located a sliding clutch 37 which, on the side facing the bevel 21, has a clutch face matching the face on the mitre. This clutch is free to slide far enough back and away from the gear 21 to disengage its clutch teeth from those of the bevel gear. Its furthest motion backwards is limited by a stop collar 38 which is set-screwed to the rod 10.

The clutch 37, which is connected to the shaft 10 by a sliding feather, can be moved in or out of engagement with the clutch face on the bevel gear by the motion of two levers 39 and 40. These levers pivot around a center 41. They always work in unison as one lever, the spring 42 and stop 52, which will later be explained, only acting to keep both levers in normal working position.

At the upper end of the lever 39 is connected the toggle link 43 which connects the lever 39 to a lever 44. The other end of the lever 44 fastens to a solenoid core 45 by a pin 46. The lever 44 pivots on a center 50. The solenoid 47 is connected in an electric circuit with one of a series of push buttons 51 adjacent to the hand wheel 11. A pull spring 48 will, when the solenoid is not energized, break the toggle formed by the lever 44 and link 43, and the core 45 will be lifted to the position shown in Fig. 4.

As the toggle is broken and the spring 48 contracts, it will pull the lever 39 towards the solenoid. This will cause the lever 40 to pull away from the solenoid and through rolls 49 in the lower end of the lever 40, which enter a circumferential groove in the clutch 37, will disengage the clutch 37 from the gear 21.

From this it will now be understood readily that, when required to adjust a certain compensator, it will be necessary only to push that particular button 51 which is assigned to this certain compensator. This will cause the solenoid to be energized. The solenoid core will be pulled down to position as shown in Fig. 2. This will

cause the toggle formed by the lever 44 and link 43 to lock and in turn push the lever 39 in the direction away from the solenoid. This in turn will cause the lever 40 with the rolls 49 to push the clutch 37 into contact with the clutch face on the gear 21. By now turning the hand wheel 11, the rod 10 will be caused to revolve. The clutch 37 will turn the bevel gear 21, which in turn will revolve the gear 23 which then will revolve the gear 25 and the adjusting screw 26.

As the adjusting screw 26 revolves it will cause the arm 30 to move up or down, as required, by the screw 26 engaging the poppet 29. This lever, being fast to the end of the shaft 31, will cause the same to turn and thereby shift the compensator arm 32 and compensator roll 33 to either side, as required for adjustment.

The only reason for the spring 42 and stop 52 is, that should it ever happen that the tops of the teeth in the clutch 27 and those on the gear 21 clash instead of closing, the spring 42 will simply compress until the rod 10 has been sufficiently revolved to release the teeth and allow the clutch to close.

On color presses, the push buttons may, if so desired, be painted in the same colors as the ink being used in the printing unit to which the certain button is allotted. By this color system the pressman no longer needs to remember which unit is printing the color in question, neither does he have to worry about which button belongs to a certain unit. He simply pushes the button having the same color which he wishes to register.

Another way of locating the buttons is, of course, to number the buttons in accordance with the number of the unit to which each button is assigned.

In Fig. 6 is shown an arrangement where the formerly hand operated adjusting rod 10 is revolved by a reversible motor 60. This motor is secured to the support rail 34 by a bracket 61. On the end of the adjusting rod 10 is mounted a gear 62 which meshes with a motor pinion 63. This gear 62 is secured to the rod 10 by a friction clutch 66 which, by a sliding feather, is kept from revolving on the rod 10. The reason for this clutch is that should, for some reason or another, undue strain be put on the revolving of the rod 10, no damage could be done as the clutch would slip and the motor could revolve. The end of the rod 10 is revolvably supported by a bearing 64 which is secured to the rail 34. Adjacent to the push button station 51 is placed another station 65 having two buttons. These buttons are so connected in the electric circuit to the reversible motor 60, that one button acts to turn the motor in clockwise direction while the other will reverse the motion. When adjusting a compensator, it will then be necessary only to press the button 51 which selects the proper compensator, then press the proper button 65 to move the compensator 33 to the right or left, as required.

In Fig. 7 is shown another way of operating the adjusting rod 10. In this case two solenoids 66 and 67 act in combination with a ratchet motion to operate the rod 10 in both directions. In this arrangement, the same as in Fig. 6, is used a two button station 68 in addition to the station 51. The solenoids are so connected in the electric circuit by a button 68, that one of the buttons acts to energize the solenoid 66 and the other the solenoid 67. When one of the solenoids is energized it will pull the core 69 or 70 respectively, into

the coil, and thereby act to move a ratchet lever 71 forward. As the lever 71 moves, a pawl 72 or 73 will engage with a ratchet wheel 74 which is secured to the rod 10, and turn the wheel 5 the length of the stroke.

When the button 68 is released, and the solenoid no longer is energized, a spring 75 will return the pawls to their original positions. As 10 the ratchet wheel 74 will move only one fixed distance when pushing a button 68, it will be necessary to give the button as many pushes as necessary to move the compensator the required distance.

The pawls are so arranged that, at the neutral 15 position of the stroke, they rise out of contact with the ratchet wheel, and will not again engage with the wheel before being urged in a forward direction by the action of the solenoids. The solenoids and ratchet motion are all supported by a support bracket 76 which is securely fastened to the support rail 34. By pushing one, or the other, of the buttons 68 the rod 10 may be turned in the required direction for adjusting 20 purposes.

Having thus described my invention and the 25 advantages thereof, I do not wish to be limited to the details herein disclosed, otherwise than as set forth in the claims, but what I claim is:

1. In a printing press, the combination with 30 a plurality of movable compensators all engaging the web and forming loops therein, of a single means by which all, and any, of said compensators may be adjusted and means connecting said single means with each of said compensators.

2. The combination with guide rolls for guiding a web in a printing plant, and a plurality of compensator rolls engaging and forming loops in 40 said web, adjustable to compensate for any give and take in the web, of a rod extending throughout a series of said compensators, means for rotating said rod, an adjusting rod for each compensator, independent means for connecting each adjusting rod to the first named rod, a push button for each compensator, and means whereby 45 each push button controls the connection of the first named rod with an individual adjusting rod designed to cooperate with that push button.

3. In a printing press, the combination with a 50 plurality of movable compensators all engaging the web and forming loops therein, of a rotatable

longitudinal rod, a plurality of adjusting rods adjacent thereto, means connecting each of said adjusting rods to a compensator for adjusting it, the said longitudinal rod constituting a single means for operating all and any of said adjusting rods and thereby controlling the compensators. 5

4. In a printing press, the combination with a plurality of movable compensators all engaging the web and forming loops therein, of a rod 10 connected for operating a plurality of the compensators, manual means for rotating said rod, a series of push buttons, solenoids and electric wires, each running from one button to one of the solenoids, an adjusting screw for adjusting 15 each compensator individually, and means connecting each adjusting screw with a solenoid, the solenoids being individually connected to their adjusting screw for operating them when the respective solenoid is energized. 20

5. In a device for adjusting a compensator, the combination of a solenoid having a plunger, a lever connected with said plunger to be operated thereby, a link pivoted to the end of the lever, a second lever pivotally connected with the link 25 to form a toggle, a spring connected with the toggle at its joint to normally move the first named lever to a position to draw the plunger part way out of the solenoid when it is not energized, a compensator adjustor, and a clutch operated 30 by the second lever for connecting the compensator adjustor with a source of power.

6. In a web-using machine, the combination with a plurality of compensators capable of being adjusted to lengthen or shorten a loop of 35 web, a single operating means adapted to operate in forward or reverse direction, of means for selectively connecting any one or more of the compensators to the single operating means.

7. In a printing press, the combination with a 40 plurality of movable compensators all engaging the web and forming loops therein, a series of push buttons, solenoids and electric wires, each running from one button to one of the solenoids, an adjusting screw for adjusting each compensator individually, and means connecting each 45 adjusting screw with a solenoid, the solenoids being individually connected to their adjusting screw for operating them when the respective solenoid is energized. 50

ARNOLD A. SCHWARTZ.
